UNITED STATES PATENT OFFICE.

MAURICE K. MCGRATH, OF NEW YORK, N. Y., ASSIGNOR TO WESTERN ELECTRIC COMPANY, INCORPORATED, OF NEW YORK, N. Y., A CORPORATION OF NEW YORK.

SELECTOR-SWITCH.

1,251,795.

Specification of Letters Patent.

Patented Jan. 1, 1918.

Application filed June 12, 1916. Serial No. 103,228.

To all whom it may concern:

Be it known that I, MAURICE K. MCGRATH, a citizen of the United States, residing at New York, in the county of New York and State of New York, have invented certain new and useful Improvements in Selector-Switches, of which the following is a full, clear, concise, and exact description.

10 This invention relates to electrically-operated switching devices for use in automatic telephone systems.

One object of the invention is to obtain a switching device in which a brush carriage is capable of moving at high speed over large groups of contacts, and where braking action is applied to the brush carriage to stop the same gradually under all conditions; thus admitting of the brush carriage 20 being of heavier and more robust construction, since its design is not limited by consideration of rapid acceleration and retardation, which are usually controlling factors in the design of switches intended to be 25 actuated by rapid impulses of current.

A further object of the invention is the provision of switching control means in which a light and readily movable stop member may be moved to a desired position during the continuous movement of the heavier brush-supporting member of the switch.

Another object is to effect the utilization of the mass of movable parts to aid and accelerate the movement of the switch in reaching the desired position.

Additional objects are to effect common operation of the parts of the switch structure; and to effect the resetting of the device to normal through actuation of a single 40 part of the device.

Still other objects are to effect the positive locking of the stop mechanism against overthrow; to effect a gradual stopping of the mechanism, thus obviating the jar attendant to quick stopping; and to effect the balanced operation of the stop-setting means.

In a step-by-step operated switch, the speed with which the brush-supporting member may be moved is limited by the mass of the brush and its movable support, owing to the comparatively great inertia of the moved member. In the present invention, a light and readily rotatable stop is moved step-by-step, and the comparatively heavy

switching device is caused to follow said stop in a continuous movement, thereby permitting a much more rapid operation of the switch.

When a switch is taken for use, an auxiliary switch is operated to release the holding means for the brush-support. The support then moves at high speed to its proper group position, under control of the stop-setting member in accordance with the digit impulses sent by the subscriber. The auxiliary switch acts after the group has been selected to associate the holding means with the switch bar and to disengage the stop-setting stepping members. If the switch is employed as a final switch, impulses corresponding to the units are then sent to step the switch bar at a slower speed to engage the brushes with the desired line.

Referring to the drawings, Figure 1 is a side elevation, partly in section, of the operating mechanism forming the subject of the present invention; Fig. 2 is a cross-section on the line 2-2 of Fig. 1; Fig. 3 is a cross-section on the line 3-3 of Fig. 1; Fig. 4 is a cross-section illustrating the manner of joining the stop member to the gear wheel, which is moved by the brush-supporting element; Fig. 5 is a cross-section on the line 5-5 of Fig. 4, and Fig. 6 is a detached view showing the side-switch wipers and contacts 85 therefor.

In the present disclosure, the invention is shown as applied to a switch of the panel type, which may be similar to that disclosed in Craft and Reynolds Patent No. 1,123,696, 90 although any desired type of panel switch may be substituted for use with the present operating mechanism.

In Fig. 1, 1 indicates a supporting shaft to which a brush set 2 is secured. A series 95 of contacts 3 is provided for the brush set. Secured to the shaft 1 at its lower end is an extension 4, which will hereinafter be referred to as an elevating bar. The elevating bar 4 is provided on one edge with a series 100 of teeth 5 arranged for operative engagement with the teeth of the gear-wheel 6 mounted on a shaft 7. The opposite edge of the bar 4 is provided with a series of ratchet teeth 8 adapted to be engaged by a 105 stepping pawl 9 and a holding pawl 10. The bar 4 and shaft 1 are slidably but non-rotatably supported in any desired manner.

Also rotatably mounted on the shaft 7 is an escape-wheel 11. The escape-wheel 11 and the gear-wheel 6 are connected by means of the coil spring 12, the outer end of which 5 is secured to the gear-wheel 6, the inner end being secured to the escape-wheel 11. The spring brake-shoe 13 is secured at one end to the escape-wheel 11, and has the laterally extending stop portion 14 at the other 10 end. This brake-shoe curves inwardly so as to lie eccentric to the shaft 7. Pivotedly secured to the gear-wheel 6 is a brake member 15, which is normally held in engagement with the shaft 7 by means of a spring 16. Upon rotation of the gear-wheel 6 in 15 an anti-clockwise direction with relation to the escape-wheel 11, the brake member 15 will be engaged with increasing force by the brake-shoe 13, and the gear-wheel will be stopped when it reaches a definite relative 20 position to the escape-wheel. Due to the centrifugal action of the brake member 15, the force of the braking action increases as the speed of the wheel 6 increases. The 25 parts are thus gradually brought to the stopping position and excessive jar is avoided.

The escape-wheel with the stop mechanism just described, is the light-setting stop member above referred to, and is arranged 30 to be rotated in an anti-clockwise direction, as viewed in Fig. 1, by means of the stepping members 17 and 18 located on opposite sides of the ratchet-wheel 11 and acting to produce a balanced movement of the wheel. These stepping members have a common 35 pivotal connection to the operating lever 19 by means of the rivet or pin 20. The spring 21 tends to force the stepping members 17 and 18 into engagement with the ratchet-wheel 11. The stepping members are, however, maintained retracted during certain 40 operations of this portion of the switch by means of the cam member 22 when positioned between the rearwardly extending portions of the stepping members 17 and 18. The member 22 is carried by an arm 45 pivotally mounted in any suitable manner in a clip 23 carried by the frame, and is provided with a spring 24, which tends to move the cam to an inoperative position. The member 22 is provided at its rear end with an anti-friction roller 25 which is arranged 50 to be operatively engaged by a cam 55 surface on the shaft or change-over bar 26. The bar 26 is slidably mounted in the clips 27 and 28 and has a plurality of functions. It controls the operative position of the pawls 9 and 10 and of the cam 22. A spring 55 60 29, which has one end secured to the lower end of the bar 26 and the other end secured to a pin fixed to the switch frame, tends to move the bar in a downward direction, and the downward movement is controlled by 65 the escape-wheel 30 through the medium of

the detent 31, which, in turn, is operated by the electromagnet 32. A collar 33, mounted on the shaft 34, carries a ratchet wheel 35, arranged to be engaged by a pawl 37 pivotally carried by a lever 36 fulcrumed on the shaft 70 34. The opposite end of the lever 36 is provided with an elongated slot 38, in which is positioned the pin 39 secured to the bar 26. Fixed to the lever 36 are the wipers 39, 40, 41, 42, 43 and 44. These wipers and 75 the contacts 45 arranged to be engaged thereby, are in the nature of an auxiliary or side switch, and the brushes 39 to 44 inclusive are moved one step with each energization of the magnet 32. 80

The ratchet-wheel 11 is rotated by the forward and backward movement of the stepping members 17, 18 by means of the bar 19, which is pivotally mounted on the pin 46. The lever 19 is provided with an 85 armature 47 of the stepping magnet 48. The lever 19 is provided at its upper end with an angular extension 49 to which is secured the stepping pawl 9. The spring 50, one end of which is secured to the arm 49 90 and the other to the upper portion of the pawl 9, tends to force said pawl into engagement with the ratchet teeth 8. The lower end of the pawl 9 is provided with an anti-friction roller 51, and is arranged 95 to be engaged by the cam 52 on the shift bar 26 in order to cause said pawl to assume an inoperative position. The holding pawl 10 is pivotally supported on the fixed pin 53, and is provided with a spring 54 100 which tends to move said pawl into engagement with the teeth 8. The lower end of the pawl member 10 is provided with an anti-friction roller 55, which is arranged to be engaged by a cam 56 on the shift bar 26 in 105 order to hold said pawl retracted.

The rod 4 is provided with an extension 57 which engages the lever 36 when the rod approaches its normal position on upward movement. On continued movement of the 110 bar 4, the lever 36 moves the change-over bar 26 to bring an insulating stud 58 thereon into engagement with contact 59, forcing it upward to engage contact 60. The closure of these contacts may be employed to 115 cut off the interrupter current for the magnet 48. The bar 4 will move slightly above normal position, and to drop it back a cam 61 is provided on the cam shaft 26 which, at its upper limit, disengages pawl 9 from 120 the rack 8, allowing the pawl 10 to drop into the lowermost tooth of the rod 4. In this position the pawl 9 again engages the rod.

The ratchet wheel 11 carries in fixed relation to it a toothed wheel 64, and mounted on a stud 65, secured to the switch frame, is a pawl 66 toothed at the end to engage said toothed wheel. A spring 67 tends to hold this pawl in engagement with said toothed 125 130

wheel. The upper surface of the detent 18 has a cam surface 68 on which a pin 69 carried by the pawl 66 rides. In the position shown in Fig. 1, the pawl is inactive, but when the cam 22 is withdrawn, the stepping members 17 and 18 are drawn into engagement with the ratchet wheel 11, and pawl 66 engages toothed wheel 64 to lock it so it will not be moved by the weight of the elevator rod 4, when it is brought to rest by the engagement of member 15 with the brake shoe 13. On actuation of magnet 48 when the stepping members 17 and 18 are in engagement with the ratchet wheel 11, 15 the detent 18 is moved forward and pin 69 on pawl 66 rides up on cam 68 of stepping member 18, thus withdrawing the pawl and permitting actuation of ratchet wheel 11 by said stepping members as before described. On retractive movement of said stepping member, the pawl 66 will again engage with the toothed wheel 64 to prevent further movement, thus preventing overthrow in a downward direction.

25 When in its normal position, the switch is so positioned that the brushes are at the top of the terminal bank instead of at the bottom, as is usual with switches of this type.

30 The device operates as follows: When a switch is selected for use, a single impulse is sent through the magnet 32, which operates the detent 31 and permits one step of the escape-wheel 30. This movement causes the cams 52 and 56 to engage the rollers 51 and 55 respectively, and retract the stepping pawl 9 and the holding pawl 10. It also permits the roller 25 to be forced into the notch 62 and thus remove the cam 22 from between the projecting ends of the stepping members 17 and 18. A series of impulses is now sent through the magnet 48, causing a rapid reciprocating movement of the stepping members 17 and 18. With 35 each forward movement, the point of the stepping member 17 engages one of the teeth of the ratchet-wheel 11 and revolves it slightly over half a step. This permits the point of stepping member 18 to drop behind one of the teeth of the ratchet-wheel 11, and upon the retraction of the detents, due to the spring 63 secured to the lever 19 and a pin on the switch frame, the action is reversed, the ratchet-wheel being again 40 advanced slightly over half a step by the stepping member 18, thus permitting the detent 17 to drop behind the next tooth. In this manner, the stop member is stepped around until the end of the series of impulses. With the first step of the ratchet-wheel 11, the stop 14 on brake-shoe 13 is moved out of operative engagement with the brake-member 15. The brush supporting shaft 1 begins to move downwardly, due 45 in part to the action of gravity, and partly

to the tension produced in the spring 12. In the usual operation of the device, the stop member will be moved more rapidly than the switch will follow, and will reach the set position before the brake member 15 again engages the stop 14. Should it be desired to move the brushes to a position near the bottom of the terminal bank, the switch shaft may reach sufficient momentum to overtake the stop member; but this will in 50 no way affect the stopping of the device, as the brake 15 will immediately engage the shoe 14 and cause the downward movement of the shaft 1 to be retarded. When, however, the stop has moved to its set position, the brake 15 continues its movement along the brake-shoe 13 until it is brought into engagement with the stop 14. At this time the brush set 2 will occupy a position below the last terminal in the group of terminals to which access is desired. Another impulse is now transmitted through the magnet 32, causing the change-over bar 26 to move downward another step. The cams 52 and 56 are now moved so as to occupy a 55 position below the rollers 51 and 55, and permit the pawls 9 and 10 to again engage the ratchet teeth 8. The roller 25 also rides out of the notch 62 and the cam member 22 is positioned between the rearwardly extending ends of the stepping members 17 and 18 so that the ratchet-wheel 11 is free to rotate. Another series of impulses will now be transmitted through magnet 48. This time it will operate the pawl 9 to cause 60 a step-by-step upward movement of the brush-supporting shaft 1. At the end of the selection, the usual change-over or movement of the side-switch wipers may be accomplished by sending another impulse 65 through magnet 32. As the wipers 39 to 44 inclusive are fixed to the lever 36, they will be moved from one contact 45 to another upon each energization of the escape magnet 32.

70 Upon the termination of the conversation or when disconnection is desired, a circuit will be completed through the magnet 48 in series with an interrupter, thus causing armature 47 to be repeatedly attracted and retracted, thus actuating the pawl 9 to step up the switch until it reaches its normal or uppermost position, when the circuit through the magnet 48 may be broken by the contacts 59 and 60 or in any desired manner. The pawl 10 acts to prevent return movement of the bar 4. The bar 4 is provided with an extension 57 which engages the lever 36 as the switch approaches its normal position and returns said lever to the 75 position shown in Fig. 1, or its normal position.

76 The lever 36 will in turn move the bar 26, carrying the cams 52 and 56 over their respective pawl rollers 51 and 55. The cams 80

52 and 56 are so made as to be deflected under spring tension so as to allow of their passing their respective rollers in upward movement of the bar 26, but to withdraw 5 the pawls 9 and 10 in the downward movement. The elevator bar will have been raised slightly above normal position by this action, bringing the cam 61 on the bar 26 into contact with the roller 51 and dis- 10 engaging the pawl 9, whereupon the elevator bar 4 drops until the pawl 10 engages in the lowermost tooth thereof. In the upward movement of the lever arm 36, the pawl 37 will have passed over the next tooth on 15 ratchet wheel 35, and on the bar 4 being re-set from its overthrow position, will return, turning ratchet wheel 35 to bring contact 40 into engagement with the first of contacts 45. The bar 26 will have been permitted 20 to drop sufficiently to disengage stud 58 from contacts 59 and 60 which control the inter- 25 ruptor sending impulses to magnet 48 at completion of conversation, and to disen- gage the cam 61 from roller 51.

25 In moving back to normal, the pawls 9 and 10 are continuously actuated, while the stepping members 17 and 18 are also actuated for the very brief interval while the roller 25 is passing the notch 62. This actua- 30 tion of the stepping members, however, is without effect on the return operation of the switch, as should the stepping members engage the ratchet-wheel 11, the spring 12 will only be wound slightly and will be re- 35 leased after the notch 62 is passed and the stepping members disengaged. The pawls 9 and 10 prevent downward movement under such conditions. The tension of the spring 12 will then return the ratchet-wheel 11 to 40 its normal position relative to the wheel 6.

What is claimed is:

1. In an electrically operated switch, a movable contact, a support therefor, groups of stationary contacts engaged by said mov- 45 able contact, means for moving said sup- port, means for stopping said support when said movable contact has reached the desired group, means to move said support to the desired contact in said group, means to re- 50 turn said support to its normal position, and common operating means to actuate all of said means.

2. In an electrically operated switch, a movable contact, a support therefor, groups 55 of stationary contacts engaged by said mov- able contact, means for moving said support, means for stopping said support when said movable contact has reached the desired group, means to move said movable contact 60 to the desired contact in said group, means to return said support to its normal position and a common electro-magnet for operating said means.

3. In an electrically operated switch, an 65 auxiliary rotatable switch, a movable brush-

supporting bar, electromagnetic means to rotate said auxiliary switch out of normal position, means mechanically controlled thereby to release said bar, means to restore said bar to normal position, and means con- 70 trolled by return movement of said bar to rotate said auxiliary switch to normal posi- tion.

4. In an electrically operated switch, an auxiliary switch, a movable brush-support- 75 ing member, mechanism to actuate said member, and a bar actuated by said auxiliary switch to control the operation of said mechanism, said bar being reset to normal position by said auxiliary switch on its re- 80 turn to normal.

5. In an electrically operated switch, a movable brush-supporting member, an aux- 85 iliary switch, means normally engaging said member to hold it in normal position, means to move said member toward said position when it is out of normal, and means me- 90 chanically actuated by said auxiliary switch to disengage said engaging means from said member to release said member, said disen- gaging means being reset to normal position by said auxiliary switch.

6. In an electrically operated switch, a movable brush-supporting member, an aux- 95 iliary switch, a bar operated on movement of said auxiliary switch, means controlled by said shaft to release said member, means to return said member to normal position, and means whereby said auxiliary switch is reset to normal position by the return of 100 said member to normal.

7. In an electrically operated switch, switch contacts therefor, a movable toothed brush-supporting member governing en- 105 gagement of said contacts, an actuating pawl normally engaging said member, a holding pawl for engaging said member, a bar having cams to engage said pawls, means to operate said bar to move said cams to withdraw said pawls to release said member, 110 means to move said member on its release, and means to move said actuating pawl to step said member.

8. In an electrically operated switch, switch contacts therefor, a movable toothed brush-supporting bar governing engage- 115 ment of said contacts, an actuating pawl normally engaging said bar, a holding pawl for engaging said bar, a cam shaft having cams to engage said pawls, a mechanism to 120 operate said shaft to cause said cams to withdraw said pawls to release said bar in one position and to move other of said cams to release said actuating pawl in another posi- 125 tion, means to move said bar on its release, means to move said actuating pawl to step said bar, means on said bar to move said mechanism to position said shaft so other of said cams release said actuating pawl, thereby permitting said bar to move back 130

a step, and means controlled by said back movement to reset said mechanism to normal position

9. In an electrically operated switch, 5 a movable contact, a support therefor, a stop for determining the stopping position of said support, a ratchet wheel to move said stop, a stepping member to operate said ratchet wheel, means to control engagement 10 of said stepping member with said ratchet wheel, and locking means controlled by said stepping member to lock said stop means against movement.

10. In an electrically operated switch, 15 a movable contact, a support therefor, a stop for determining the stopping position of said support, a ratchet wheel to move said stop, a stepping member to operate said ratchet wheel, cam means on said stepping 20 member, a locking pawl operated by said cam, and means movable with said stop to be engaged by said pawl to prevent movement of said stop

11. In an electrically operated switch, 25 a movable contact, a support therefor, a stop for determining the stopping position of said support, a ratchet wheel to move said stop, a stepping member to operate said ratchet wheel, a locking pawl, a locking 30 wheel movable with said stop arranged to be engaged by said pawl, and cam means on said stepping member normally holding said pawl in non-engaging position.

12. In an electrically operated switch, 35 brushes, supporting means for said brushes, stop means for determining the stopping position of said supporting means, rotatable means connecting said bar to said stop means, and a brake between said stop and rotatable means.

13. In an electrically operated switch, 40 brushes, supporting means for said brushes, stop means for determining the stopping position of said supporting means, rotatable means connecting said supporting means to 45 said stop means, a brake shoe on said stop means, and a brake member eccentrically mounted on said rotatable means to engage said shoe.

14. In an electrically operated switch, 50 brushes, a movable brush-supporting means, a stop means for determining the stopping position of said supporting means, a ratchet wheel to move said stop means, and reciprocating pawl means operable to turn said wheel on movement in both directions.

15. In an electrically operated switch,

brushes, a movable brush-supporting means, a stop means for determining the stopping position of said supporting means, a ratchet 60 wheel to move said stop means, and means to operate said wheel comprising reciprocating pawls, one operatively engaging said wheel on one side when the pawls move in one direction, and another pawl operatively engaging said wheel on the opposite side on movement of the pawls in the other direction.

16. In an electrically operated switch, a contact, a movable support therefor, a 70 mechanical stop for determining the stopping position of said support, means to move said support at high speed until said stop is encountered, and means to move said support at slow speed subsequent to said encounter.

17. In an electrically operated switch, a plurality of groups of contacts, movable contacts for association with any of said contacts, a movable support for said movable 80 contact, a mechanical stop for determining the group to which said support is to move, means for moving said support at high speed until said stop is encountered, and means to move said support at slow speed subsequent 85 to said encounter to associate the movable contact with a desired contact in the selected group.

18. An automatic selective switch having 90 a movable terminal member, a multi-position auxiliary switch for controlling the operating circuits of said member, and means carried by said auxiliary switch for mechanically controlling the movement of said member.

19. An automatic selective switch having 95 a movable terminal carrying member, mechanical means coöperating with said member for determining the movement thereof, a multi-position movable circuit controlling 100 element, and means carried by said element for directly controlling said mechanical means.

20. An automatic selective switch, fixed 105 circuit terminals, brushes coöperating therewith, means for actuating said brushes, a multi-position auxiliary switch for controlling the operating circuits of said automatic switch, and means carried by said auxiliary switch for mechanically controlling 110 said actuating means.

In witness whereof, I hereunto subscribe my name this 9th day of June, A. D., 1916.

MAURICE K. McGRATH.
